United States Patent Office

Des. 220,565
Patented Apr. 27, 1971

220,565

SHUTTER

Raymond W. Sickler, R.D. 2, Wellsville, N.Y. 14894

Filed Dec. 5, 1969, Ser. No. 20,372

Term of patent 7 years

Int. Cl. D25—02

U.S. Cl. D13—1

FIG. 1.

FIG. 2.

FIG. 3.

FIG. 1 is a perspective view of the front face of the shutter, showing my new design; and

FIG. 2 is a rear perspective view; and

FIG. 3 is a cross-sectional view along the lines 3—3 of FIG. 1, looking in the direction of the arrows.

I claim:

The ornamental design for a shutter, as shown.
